DESIGN FOR A CLOTHES-WASHING STIRRER OR THE LIKE

Frank B. Manning, University City, Mo.

Application September 13, 1943, Serial No. 111,110

Term of patent 14 years

To all whom it may concern:

Be it known that I, Frank B. Manning, a citizen of the United States and a resident of University City, in the county of St. Louis and State of Missouri, have invented a new, original, and ornamental Design for a Clothes Washing Stirrer or the like, of which the following is a specification, reference being had to the accompanying drawing, forming part thereof.

Fig. 1 is a top plan view of a clothes washing stirrer showing my new design,

Fig. 2 is a side elevational view of said stirrer; and

Fig. 3 is an edge elevational view of said stirrer.

I claim:

The ornamental design for a clothes washing stirrer or the like, as shown.

FRANK B. MANNING.
